UNITED STATES PATENT OFFICE

121,212

DESIGN FOR AN INITIAL KEY CHAIN OR THE LIKE

Edwin S. Mix and Harold C. Vaisey, Rochester,
N. Y., assignors to Hickok Manufacturing Company, Inc., Rochester, N. Y., a corporation of New York

Application January 18, 1940, Serial No. 89,563

Term of patent 7 years

To all whom it may concern:

Be it known that we, Edwin S. Mix and Harold C. Vaisey, citizens of the United States, residing at Rochester, in the county of Monroe and State of New York, have invented a new, original, and ornamental Design for Initial Key Chains or the like, of which the following is a specification, reference being had to the accompanying drawing, forming part thereof.

In the drawing, the figure is a perspective view of an initial key chain showing our new design, parts being shown in dotted lines.

We claim:

The ornamental design for an initial key chain or the like, substantially as shown.

EDWIN S. MIX.
HAROLD C. VAISEY.
